UNITED STATES PATENT OFFICE

107,373

DESIGN FOR A LACE FOR A CAPE OR SIMILAR ARTICLE

Lawrence E. Hart and Herbert E. Lewy, New
York, N. Y.

Application July 20, 1937, Serial No. 70,540

Term of patent 3½ years

To all whom it may concern:

Be it known that we, Lawrence E. Hart and Herbert E. Lewy, citizens of the United States of America, residing in the city of New York, county of New York, and State of New York, have invented a new, original, and ornamental Design for a Lace for a Cape or Similar Article, of which the following is a specification, reference being had to the accompanying drawing, forming part thereof.

The figure of the drawing is a plan view of a

lace for a cape or similar article showing a little more than half of the complete design, one-half of the design being indicated on the drawing by dot and dash lines. The characteristic feature of the design resides in the lace pattern.

We claim:

The ornamental design for a lace for a cape or similar article substantially as shown and described.
